UNITED STATES PATENT OFFICE.

JASPER SPEESE, OF MILTON, PENNSYLVANIA.

AUTOMOBILE-COAT.

1,331,394.

Specification of Letters Patent. Patented Feb. 17, 1920.

Application filed May 5, 1914. Serial No. 836,493.

To all whom it may concern:

Be it known that I, JASPER SPEESE, a citizen of the United States, residing at Milton, in the county of Northumberland and State 5 of Pennsylvania, have invented new and useful Improvements in Automobile-Coats, of which the following is a specification.

This invention relates to automobile coats, and it has for its object to produce a garment of this class which will be especially convenient not only while riding, but especially while working about the machine for the purpose of making such emergency repairs as may be required.

15 A further object of the invention is to produce a coat garment of simple construction in which the skirts may be fastened about the limbs of the wearer in a simple, convenient and efficient manner.

20 A further object of the invention is to produce a coat garment of the character described in which the sleeve may be fastened about the wrist and adjusted as to length in a convenient manner for the purposes set 25 forth.

With these and other ends in view which will readily appear as the nature of the invention is better understood, the same consists in the improved construction and novel 30 arrangement and combination of parts which will be hereinafter fully described and particularly pointed out in the claims.

In the accompanying drawings has been illustrated a simple and preferred form of 35 the invention, it being, however, understood that no limitation is necessarily made to the precise structural details therein exhibited, but that changes, alterations and modifications within the scope of the claims 40 may be resorted to when desired.

In the drawings,—

Figure 1 is a front view showing a simple and preferred form of the invention.

Fig. 2 is a rear view of the same.

45 Fig. 3 is a perspective view showing the coat applied to a person.

Fig. 4 is a detail side view illustrating a slight modification, particularly with respect to the sleeve of the coat.

50 Fig. 5 is a perspective view showing the modified sleeve applied.

Fig. 6 is a perspective detail view illustrating a further modification.

Fig. 7 is a sectional detail view taken sub- 55 stantially on the line 7—7 in Fig. 3.

Fig. 8 is a sectional detail view taken substantially on the line 8—8 in Fig. 5.

Corresponding parts in the several figures are denoted by like characters of reference.

In the drawings, the invention has been 60 shown applied to a coat made of light material and of the variety known as "duster," but it is obvious that the invention may be applied to coats of various patterns and of any desired material.

65 The coat is provided in the back portion thereof with the customary vertical slit 15 extending upwardly from the lower edge and dividing the lower part of the garment into the skirts 16, 16. Each of said skirts is 70 provided on the outer face thereof with a row of fastening members 17 extending diagonally from the slit 15 to the bottom edge of the garment. Each of the skirts is provided adjacent to the front edge thereof with a 75

corresponding row of fastening members 18 arranged in a vertical row on the inner face of the skirt, said fastening members being of a character to coöperate with the fastening members 17. For purposes of illustration 80

fastening members of the ordinary friction "snap" variety have been shown, but no limitation whatever is intended in this respect. Thus, for instance, the respective 85

fastening members or elements might consist of buttonholes and buttons, respectively. The front edge of each skirt is usually provided 90 with a hem 19 which affords sufficient backing and reinforcement for the fastening members; each skirt is preferably provided 95 with a diagonally disposed reinforcing strip 20 on the back portion thereof to afford a backing for the fastening members 17.

Each sleeve of the garment is provided with a connecting element, such as a buckle 95 21, which is engaged by a strap or billet 22 connected with and depending from the shoulder portion of the garment. The purpose of this is to enable the sleeve to be

pulled up about the wrist of the wearer so as 100 not to interfere with the free use of the hand, as will be readily seen by reference to Figs. 3 and 5. The buckle or connecting element 21 may be attached directly to the outside 105 of the sleeve, as seen in Figs. 1 and 3, or it may be connected with the sleeve by divergent straps 23, as seen in Figs. 4 and 5,

thereby equalizing the pulling strain on opposite sides of the sleeve.

110 For the purpose of enabling the wrist por-

tion of the sleeve to be constricted around the wrist of the wearer so as to be held in a reasonably tight and effective manner, fastening members may be provided. These 5 fastening members which may be of the friction snap variety may be arranged in pairs at opposite sides of the sleeve interiorly of the latter, as clearly seen in Fig. 7, and as also indicated in Fig. 3, said fastening 10 members or elements being designated, respectively, by 24 and 25. Coöperating fastening elements 26, 27 may also be arranged exteriorly upon the sleeve, as indicated in Figs. 5 and 8, so that by wrapping 15 or folding the sleeve portion about the wrist of the wearer, the said fastening elements may be brought into alinement for effective engagement with each other. Again, as illustrated in Fig. 6, the sleeve may be con- 20 stricted at the end thereof and provided with a wrist band 28 having coöperating fastening elements 29 and 30 which, when brought into engagement with each other, will clasp the wristband sufficiently tight upon the 25 wrist of the wearer.

From the foregoing description, taken in connection with the drawings hereto annexed, the operation and advantages of this invention will be readily understood. It 30 will be seen that by simply folding the rear portion of the skirt about the limb of the wearer, the diagonal row of fastening members 17 will be brought into effective alinement with the coöperating fastening members 18 at the front edge of the skirt, thus 35 enabling the skirts to be secured snugly about the limbs of the wearer, as clearly seen in Fig. 3. The triangular flaps of the skirts below the diagonal rows of fastening members 17 will be positioned in proximity 40 to the knees of the wearer. Auxiliary co- 45 operating fastening elements 31, 32 for the points of these triangular flaps may be provided exteriorly on the flap and interiorly on the skirt, as indicated in Fig. 1, when desired.

All automobile users are familiar with the annoyance caused by having the coat skirts drag in the dust or dirt while stooping about 50 the machine and, likewise, with the annoyance caused by the coat sleeves interfering with adjustments and repairs of various kinds. By this invention the skirts of the coat may be fastened snugly about the limbs 55 of the wearer, preventing dragging in the dirt and also protecting the limbs and garments in an effective manner from dust while riding. The sleeves may be quickly

fastened and tightened about the wrist and then shortened by engagement of the buckles 60 21 with the straps 22, thus providing a simple and inexpensive garment which is eminently suited for the purposes set forth. It will, of course, be understood that while the garment is designated as an automobile 65 coat, it may be usefully employed for many purposes needless to enumerate.

Having thus described the invention, what is claimed as new, is:—

1. A coat garment having a slit in the back 70 extending upwardly from the lower edge to form two separate skirts having substantially vertical front and rear side edges, each skirt being provided with a diagonal row of fastening elements extending between the slit and the lower edge and defining a triangular flap, and each skirt being also provided with a vertical row of fastening elements arranged adjacent and in parallel relation to the front edge thereof for co-operation with the diagonal row of fastening 80 elements, the fastening element defining the highest point in the triangular flap of each skirt in normal position being located materially below the top of the vertical row of 85 fastening elements of the skirt, whereby the garment will be fulled in the seat to afford freedom when the elements are fastened together.

2. A coat garment open in the front and 90 having a slit in the back extending upwardly from the lower edge to form two separate skirts with vertical front and rear edges, each skirt being provided in the rear portion thereof with a row of fastening elements defining a triangular flap, a row of fastening elements arranged in the front of each skirt to co-act with the aforesaid fastening elements to secure the front and rear marginal edges together and independent co-acting 95 fastening elements arranged to secure the triangular portion of each skirt; the fastening element defining the highest point in the triangular flap of each skirt in normal position being located materially below the top of the vertical row of fastening elements of the skirt, whereby the garment will be fulled in the seat and a reinforcing backing for the knee will be produced.

In testimony whereof I affix my signature 110 in presence of two witnesses.

JASPER SPEESE.
